(57) **CLAIM**

The ornamental design for a waste collecting container, as shown and described.

DESCRIPTION

FIG. 1 is a top isometric view of the visible above ground parts of a waste collecting container of our invention;

FIG. 2 is a front elevational view thereof;

FIG. 3 is a right side elevational view thereof, the left side is a mirror image therof;

FIG. 4 is a right side elevational view thereof, with a filling lid in an open position;

FIG. 5 is a rear elevational view thereof;

FIG. 6 is a rear isometric view thereof; and,

FIG. 7 is a top plan view thereof.
